Z. OSTENBERG

COATING MACHINE BLOCK ADJUSTER

Filed Aug. 31, 1921

UNITED STATES PATENT OFFICE.

ZENO OSTENBERG, OF SAN JOSE, CALIFORNIA, ASSIGNOR TO THE CALTEX COMPANY,
OF SAN JOSE, CALIFORNIA, A CORPORATION OF CALIFORNIA.

COATING-MACHINE BLOCK ADJUSTER.

Application filed August 31, 1921. Serial No. 497,309.

To all whom it may concern:

Be it known that I, ZENO OSTENBERG, a citizen of the United States, and resident of San Jose, in the county of Santa Clara and 5 State of California, have invented certain new and useful Improvements in Coating-Machine Block Adjusters, of which the following is a specification.

This invention relates to coating machines 10 of the general type set forth in my copending application, Serial No. 440,101, filed Jan. 26, 1921, in which movable blocks are provided for regulating the width of the coating as applied to the material coated.

15 It is the object of my invention to provide means for adjusting the blocks referred to so that the same, after once being set, will automatically conform to changes in the width of the cloth.

20 In the drawing,—

Figure 1 is a side view of my invention in position, partly in elevation and partly in section.

25 Figure 2 is an enlarged sectional view through the valve shown in Figure 1.

Figure 3 is a detail perspective view of a portion of the device shown in Figure 1.

Referring more particularly to the drawings, 1 indicates a portion of a coating table 30 over which the coated material 2 passes, and 3 indicates a portion of the coating knife having a discharge orifice 3^a, the movable block 4 being set to permit the coating material to flow onto material 2 and to within a 35 short distance of its edge 5.

At 6 is shown a bracket mounted on table 1 and supporting a movable cylinder 7 and a fixed piston head 8. Piston head 8 is arranged in the center of cylinder 7 forming

40 chambers 9 and 10 therein, the said chambers being connected to valve chamber 11 by passages as 12 and 13 respectively. A suitable fluid is conveyed to chamber 11 under pressure by a flexible conduit as 14.

45 In valve chamber 11 is fitted a wedge shaped valve 15 normally closing off port 16 and operated by a crank 17 and rod 18.

Mounted on cylinder 7 and extending outwardly therefrom in parallel relation to 50 block 4 is an arm 19 carrying a pivot 20 on which is mounted a bell-crank 21, the shorter arm of which is normally in a horizontal position and carries a weight 22 and the longer arm of which is normally vertical 55 and contacts with edge 5 of the coated ma-

terial 2. The rod 18 is pivotally attached to the longer arm of the bell-crank 21 as at 23.

In the lower portion of valve chamber 11 is an exhaust port 24 normally communicating with both sides thereof as shown.

In operation the parts are all normally arranged as shown in the figure. If, however, the material 2 becomes narrower through shrinkage or any other cause, the vertical arm of bell-crank 21 follows it as to position 25 because of the weighted horizontal arm. This movement of the vertical arm operates valve 15 to position 26 whereupon fluid under pressure is passed into chamber 9 and the whole cylinder 7 and parts carried thereby are moved forwardly until the valve 15 is closed, this closing taking place when the long arm of bell-crank 21 has again assumed a vertical position. The block 4 having been moved up to position 26 the in-coated edge is maintained at the same width as before.

If the cloth widens the block 4 is moved backwardly by reversal of the valve 15 which permits the actuating fluid to enter chamber 10. In this manner the material being coated may be covered to within a predetermined distance from the edge throughout its whole length, no matter how pronounced the undulations in the edge thereof may be.

It is to be understood, of course, that while I have herein shown and described one particular embodiment of my invention, that changes in form and construction may be made within the scope of the appended claims.

I claim:—

1. In combination, a coating knife, a piston supported in fixed relation thereto, a cylinder mounted to reciprocate on said piston, means carried by said cylinder for varying the width of the discharge orifice in said knife, means for actuating said cylinder, a follower element carried by said cylinder and adapted to engage the material passed under said knife, and means operated by said element for rendering said actuating means operative.

2. In combination, a coating knife adjusting block, a cylinder attached to said block to move therewith, a stationary piston arranged in said cylinder, a support therefor, means for actuating said cylinder, an

arm carried by said cylinder in substantially parallel relation to said block, a follower element carried by said arm, and means operated by said follower element for rendering said actuating means operative.

3. In combination, a coating knife adjusting block, a cylinder attached to said block to move therewith, a stationary piston arranged in said cylinder, a support therefor, 10 means for actuating said cylinder, an arm carried by said cylinder in substantially parallel relation to said block, a weighted bell-crank pivotally mounted on said arm, and means operated by the said bell-crank 15 for rendering said actuating means operative.

4. In combination, a coating knife adjusting block, a follower element movable therewith and means rendered operative by the

movement of said follower element for actuating said adjusting block.

5. A coating knife, an adjusting block mounted to move longitudinally thereof, a follower element mounted to maintain positive contact with the edge of the material being coated and movable with said block, and means rendered operative by the action of said follower element for actuating said block.

6. A coating knife, an adjusting block mounted to move longitudinally thereof to define the width of the sheet of coating material discharged therefrom and means actuated by the material being coated for automatically maintaining said block in a predetermined position with relation to the edge of the said material.

ZENO OSTENBERG.
